(57) **CLAIM**

The ornamental design for a stroller cover, as shown.

DESCRIPTION

FIG. 1 is a perspective view of the first variant of the stroller cover;

FIG. 2 is a top plan view of the first variant of the stroller cover;

FIG. 3 is a bottom plan view of the first variant of the stroller cover;

FIG. 4 is a rear elevation view of the first variant of the stroller cover;

FIG. 5 is a left side elevation view of the first variant of the stroller cover;

FIG. 6 is a right side elevation view of the first variant of the stroller cover;

FIG. 7 is a front view of the first variant of the stroller cover; and,

FIG. 8 is a top view of the first variant of the stroller cover having an upwardly extended shield;

The broken lines are for environmental purposes only and form no part of the claimed design.
